UNITED STATES PATENT OFFICE.

RALEIGH J. HIMMELRIGHT, OF NEW YORK, N. Y., ASSIGNOR TO AMERICAN ARCH COMPANY, OF NEW YORK, N. Y., A CORPORATION OF DELAWARE.

LOCOMOTIVE FURNACE CONSTRUCTION.

1,417,667.

Specification of Letters Patent. Patented May 30, 1922.

Application filed April 24, 1919. Serial No. 292,251.

To all whom it may concern:

Be it known that I, RALEIGH J. HIMMELRIGHT, a citizen of the United States, residing at New York city, in the county of New York and State of New York, have invented certain new and useful Improvements in Locomotive Furnace Constructions, of which the following is a specification.

This invention has reference to the provision of means designed especially for use in locomotive furnace devices whereby an additional supply of air to mix with the combustion gases is carried into the fire box through openings in the side water legs of the fire box and is distributed equally from openings which are preferably spaced near the top of a cross bridge wall located a short distance to the rear of the flue sheet. One of the objects of this arrangement is to get a sufficient supply of air directed in the most advantageous manner and thus to secure more satisfactory combustion.

A further object of the invention is to supply means whereby air may be admitted to the fire box through pipe conduits inserted in ferrules which open through the side water legs to the atmosphere, the pipe conduits extending through a cross wall in the fire box.

30 The above as well as such other objects as may hereinafter appear, I attain by means of a construction which I have illustrated in preferred form in the accompanying drawings wherein:

35 Figure 1 is a longitudinal vertical sectional view through a locomotive fire box showing my improvements applied thereto; Figure 2 is a transverse sectional view taken on the line 2—2 of Figure 1 and Figure 3 is a partial plan view, the side walls being shown in section on the line 3—3 of Figure 2.

40 Referring now more particularly to Figures 1 and 2, it will be seen that I have there-in shown a locomotive fire box comprising outside sheets 4, 5, 6 and 7 and inside side sheets 8 and 9 with a flue sheet 10, throat sheet 10^a, and crown sheet 11, all arranged substantially as is customary in this class of apparatus.

45 Extending backward and upward from the front water wall 12 there are a series of arch tubes 13 curved as shown and connecting with the rear water wall above the fire door, these tubes being arranged to support the brick of an arch 14.

Extending transversely across the fire box at about the plane of the grate, and one third of the distance back of the front water wall 12, is provided a support 15 that carries the transverse wall 16 of refractory material 60 which has near its upper edge a row of bricks 17, recessed to receive the tubes 18 and 19 which extend inwardly from either side and have their outer ends socketed in ferrules 21, and which are provided with laterally opening discharge nozzles 20, adapted to direct in a rearward direction, the air coming through the ferrules 21 and the tubes 18 and 19.

Covering the tubes 18 and 19 I provide a series of bricks 22, which are recessed in a manner to receive the arch tubes 13 as shown in Figure 2.

By embedding the tubes 18 and 19 with their lateral outlets 20 in the refractory 75 bricks 17 of the transverse wall 16, I am enabled to secure protection for such tubes from the heat of the furnace and yet provide a channel for the ready introduction of the air into the interior of the furnace chamber 80 in a manner and at a point to procure efficient intermixing of the air and the gases. The arrangement shown also provides a means for supporting and positioning the air pipes 18 and 19 in the brick work of the 85 cross wall in such manner as to prevent displacement of said pipes while at the same time permitting free expansion and contraction thereof by reason of the sliding engagement of their ends within the ferrules 21.

It will be seen that this construction has a decided advantage over the well-known Gaines construction. In the Gaines wall the air comes up from the bottom and has to 95 pass through the bricks thus necessitating the provision of bricks properly recessed or perforated and properly arranged. The present structure is far more simple and permits of the use in the greater portion of 100 the wall of ordinary solid brick.

The bricks 22 also act to afford a support for the arch 14 and keep the latter from sliding downward upon the arch tubes.

I claim:

1. A locomotive furnace structure comprising in combination, side water walls, a transverse refractory wall provided with a series of recessed bricks, an air pipe supported and positioned by the recesses, an air passage 110

through a water wall communicating with the air pipe, the pipe having sliding engagement with the air passage in the water wall, and an air discharge opening from said pipe 5 into the furnace.

2. A locomotive furnace structure comprising in combination, side water walls, circulation tubes, a refractory arch supported on the tubes, a transverse refractory wall provided with a transversely disposed series of recessed bricks, an air pipe supported and positioned by the recesses, a transversely disposed series of bricks covering the tubes and said recesses and engaging the circulation 10 tubes and the arch, an air passage through a water wall communicating with the air pipe, the pipe having sliding engagement with the air passage in the water wall, and an air discharge opening from said pipe into the 15 furnace.

3. A locomotive furnace structure comprising in combination, side water walls, inclined circulation tubes, an arch supported on the tubes, a transverse refractory wall provided 20 with a transversely disposed series of bricks having recesses in their upper faces, an air pipe supported and positioned by the recesses, a transversely disposed series of cover 25 bricks for the tubes and the recesses, said cover bricks being adapted to engage the circulation tubes and the arch and to be held in place by the downward thrust of the arch, an air passage through a water wall communicating with the air pipe, and an air 30 discharge opening from said pipe into the furnace.

4. A locomotive furnace structure comprising in combination, side water walls, a transverse refractory wall, a recess in the upper 35 face of said refractory wall, an air inlet pipe supported and positioned by said recess, a refractory cover for said pipe and said recess, an air passage through a water wall communicating with the air pipe, the pipe having sliding engagement with the air 40 passage in the water wall, and an air discharge opening from said pipe into the furnace.

5. A locomotive furnace structure comprising in combination, side water walls, in-

clined circulation tubes, an arch on the tubes, 50 a transverse refractory wall, a recess in the upper face of said refractory wall, an air inlet pipe supported and positioned by said recess, a refractory cover for said pipe and recess, said cover being adapted to engage 55 the circulation tubes and the arch and to be held in place against the tubes and the transverse wall by the downward thrust of the arch, an air passage through a water wall communicating with the air inlet pipe, and an air discharge opening from said pipe into 60 the furnace.

6. A locomotive furnace structure comprising in combination, side water walls, a transverse refractory wall composed of a plurality of rows of bricks in the body portion thereof of solid construction and a row of recessed bricks thereabove, an air pipe supported and positioned by the recesses, an air 65 passage through a water wall communicating with the air pipe, and an air discharge opening from said pipe into the furnace.

7. A locomotive furnace structure comprising in combination, side water walls, a transverse wall supporting member within the 70 furnace in the lower portion thereof, a cross wall supported on said member, a transversely extending recess near the upper portion of the wall, an air pipe in said recess, an air passage through a water wall communicating with the air pipe, and an air 75 discharge opening from said pipe into the furnace.

8. A locomotive furnace structure comprising in combination, side water walls, a transverse wall supporting member within the 80 furnace in the lower portion thereof, a plurality of bricks on said member constituting a cross wall, a row of recessed bricks near the upper portion of said wall, an air pipe 85 in said recesses, an air passage through a water wall communicating with the air pipe, and an air discharge opening from said pipe into the furnace.

In testimony whereof, I have hereunto 90 signed my name.

RALEIGH J. HIMMELRIGHT.
